UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed September 8, 1930. Serial No. 480,396.

My invention relates to improvements in slicing machines and has for one purpose the provision of improved means for supporting the slice at the time of its severing from the 5 body of the work. Another object is the provision of improved means for deflecting the slice away from the knife which cuts it. Another object is the provision of improved means for delivering slices cut by the rotary 10 knife to a receiving tray.

Other objects will appear from time to time in the course of the specification and claims.

My invention is illustrated more or less diagrammatically in the accompanying drawings, wherein:

Figure 1 is a plan view;

Fig. 2 is a rear elevation;

Fig. 3 is a section on line 3—3 of Fig. 2;

Fig. 4 is a section on the line 4—4 of Fig. 2;

Fig. 5 is a section on the line 5—5 of Fig. 4;

Fig. 6 is a detail; and

Fig. 7 is a partial horizontal section through a variant form.

Referring to the drawings, A generally indicates a base portion upon which may be mounted in any suitable manner, a motor A¹ with a motor shaft A² and a pulley A³. A⁴ indicates a belt extending about a pulley A⁵ on the knife shaft A⁶.

B indicates a rotary knife mounted on the knife shaft A⁶ and forwardly recessed as at B¹ and rearwardly as at B².

C indicates a guard plate masking a forward face of the knife. The knife is protected from the rear by the frame or housing portion C¹ upwardly projecting from the base A. Formed with or mounted upon this frame portion C¹ is the bearing sleeve C² in which the knife shaft A⁶ is mounted. This bearing sleeve C² is forwardly flared or expanded as at C³ to terminate in an arcuate lip C⁴ which penetrates the rear recess B² of the knife as shown, for example, in Figs. 1, 3, 4 and 7.

D generally indicates a gauge plate which may be mounted on any suitable support generally indicated as at D¹. D² indicates a rotary knob whereby, through any suitable gearing or drive means the support D¹ and gauge plate D may be moved into and out of

and rearwardly away from the cutting plane. Underlying the gauge plate D is a slice support D³ in the form of an extended bar. This bar includes or has mounted thereon an elevated portion D⁴ adjacent the closest approach of the bar to the cutting edge of the knife. This raised portion D⁴ extends upwardly above the normal level of the top of the bar D³. It is to be seen, as in Fig. 4, that an end of the bar portion projects inwardly 55 past the periphery of the knife as at D⁵, this end D⁵ being more or less curved or spaced outwardly away from the rear face of the knife. Preferably the curved portion D⁵ extends or curves from the cutting edge of the 60 knife, closely approaching the knife at the cutting edge and being spaced laterally therefrom an increasing distance progressively toward the center of the knife. This form of the disposition will be clear from Fig. 4. The 70 bar D³ is also provided with a recess or downwardly and outwardly cut-away and beveled or curved portion D⁶. This cut-away portion permits the severed slice to clear or drop below the level of the raised portion or supporting abutment D⁴ and also deflects the 75 slice away from the rear face of the knife.

In order to receive the slice after it is severed, I provide any suitable receiving tray E, the details of which do not of themselves 80 form part of the present invention, but which is formed as at E¹ closely to approach the cutting plane. In order to support the material to be sliced, I provide any suitable carriage structure generally indicated as G 85 which rides along the circular supporting rail G¹ and the rectangular guide rail G². G³, G⁴ indicate downward projections or tongues from the carriage structure G which engage also sides of the guide track G² as by 90 the adjustable members G⁴. G⁵ indicates a work support positioned upon the carriage G. Preferably the level of the upper surface of the work support is substantially even with the top of bar D³. The member D⁴ projects above the surface of the bar D³ and also above the surface of the support G⁵. The edge of the carriage G⁵ approaches closely the outer edge of the bar D³ as shown, for example, in 95 Figs. 1 and 5, and when the gauge plate D is 100

in withdrawn position, the edge of the work rests upon the top of the bar D^3 as well as upon the support G^5 .

Referring to Fig. 7, a variant form of my invention in which a deflecting member is mounted, for example, upon the frame or guard portion C^2 or C^3 , I illustrate a bracket H which may be secured as by the screws H^1 to the enlarged portion C^3 of the sleeve C^2 .

10 Mounted at the outer extremity of the bracket H is a deflector generally indicated as H^2 , the forward end H^3 of which may approach or contact the end of the slice support which is beveled or cut away as at H^4 adjacent the forward end of the projection D^4 .

15 It will be realized that whereas I have shown and described a practical and operating device, nevertheless, many changes may be made in size, shape, number and disposition of parts without departing from the spirit of my present invention. I wish my drawings, therefore, and my description to be taken as in a broad sense illustrative or diagrammatic, rather than as limiting me to my particular description and disclosure in detail.

20 The use and operation of my invention are as follows:—

25 I find it preferable to support the slice at the point of severance and an efficient method of supporting it is to employ an upward projection such as the member D^4 , which lies in part on each side of the cutting plane. This projection D^4 provides a positive support for

30 the work at the point of severance and for the slice as it is being severed. As soon as the slice is actually severed it should be permitted to drop to clear from the rear of the knife. This is important in order to prevent adherence of the slice to the rear face of the knife.

35 The result of such adherence may be damage to or breaking up of the slice and bleeding of the material. In order to effect this free drop and guide action, I have cut away the

40 end of the bar as at D^7 , or provide a similar cut-away portions H^4 and H^5 in connection with the deflector H^2 . The slice, therefore, drops, its edge being free to drop, and engages the cut-away portion D^7 or H^4 . This

45 downwardly and outwardly curved or inclined cut-away portion tends to throw the slice outwardly away from the knife and it is, in practice, discharged on the tray E an inch or more away from the cutting plane.

50 In order to prevent any interference with the slice as it is severed, I find it preferable to form the portion D^5 of the bar D^3 in such fashion that it approaches the cutting edge only at the cutting point and recedes rapidly

55 therefrom as shown in Fig. 4. This prevents any tendency to wedge or catch the slice or fragments of sausage casings and the like between the knife and the member D^5 . The deflector H^2 is similarly formed and spaced.

60 65 The grease and small fragments which may

adhere to the knife are caught by a scraper J which may be adjustably mounted as by bolts J^1 upon the portion C^3 . The scraper J is positioned above the drip pan J^2 which is concealed by the end of the receiving tray E . The frame is cut away as at J^3 , the scraper J being aligned with this cut-away portion and being adapted to deliver the material to the pan J^2 .

70 I claim:—

75 1. In a slicing machine including a rotary knife and means for rotating it, a carriage and means for conveying said carriage past the cutting edge of the knife, a slice and work support positioned adjacent said carriage adapted to support the work and slice at the point of severance, and deflector means adjacent said support adapted to deflect the severed slice, said deflector means being closely adjacent but out of contact with the rear face of the knife, and being separated therefrom by a distance increasing progressively inwardly from the periphery of the knife, the approach of the deflector to the knife at the severing point being close.

80 2. In a slicing machine including a knife and means for actuating it, a carriage and means for conveying said carriage past the cutting edge of the knife, a slice and work support positioned adjacent the carriage and adapted to support the work and slice at the point of severance, said support lying on both sides of the cutting plane of the knife and closely approaching the cutting edge and overlapping the edge of the knife to the rear, said rear overlapping portion being spaced away from the opposed face of the knife by a distance increasing progressively from the cutting edge inwardly toward the axis of rotation of the knife.

85 3. In a slicing machine including a knife and means for actuating it, a carriage and means for conveying said carriage past the cutting edge of the knife, a slice and work support positioned adjacent the carriage and adapted to support the work and slice at the point of severance, said support closely approaching the cutting edge and overlapping the edge of the knife to the rear, said rear overlapping portion being spaced away from the opposed face of the knife by a distance increasing progressively from the cutting edge inwardly toward the axis of rotation of the knife.

90 4. In a slicing machine including a knife and means for actuating it, a carriage and means for conveying said carriage past the cutting edge of the knife, a slice and work support positioned adjacent the carriage and adapted to support the work and slice at the point of severance, said work support overlapping the face of the knife to the rear of the cutting plane and extending substantially rearwardly from the cutting plane, the rear overlapping portion being spaced away from

the opposed face of the knife by a distance increasing progressively inwardly from the cutting edge of the knife.

5. In a slicing machine including a knife and means for actuating it, a carriage and means for conveying said carriage past the cutting edge of the knife, a slice and work support positioned adjacent the carriage and adapted to support the work and slice at the point of severance, said work support overlapping the face of the knife to the rear of the cutting plane and extending substantially rearwardly from the cutting plane, the rear overlapping portion being spaced away from the opposed face of the knife by a distance increasing progressively inwardly from the cutting edge of the knife.

6. In a slicing machine including a knife and means for actuating it, a carriage and means for conveying said carriage past the cutting edge of the knife, a slice and work support positioned adjacent the carriage and adapted to support the work and slice at the point of severance, and a deflector associated with said work support and overlapping the edge of the knife to the rear, said rear overlapping deflector portion being spaced away from the opposed face of the knife by a distance increasing progressively inwardly from the cutting edge.

7. In a slicing machine including a knife and means for actuating it, a carriage and means for conveying said carriage past the cutting edge of the knife, a slice and work support positioned adjacent the carriage and adapted to support the work and slice at the point of severance, and a deflector associated with said work support and overlapping the edge of the knife to the rear, said rear overlapping deflector portion being spaced away from the opposed face of the knife by a distance increasing progressively inwardly from the cutting edge, said deflector portion being rearwardly downwardly and outwardly reduced.

8. In a slicing machine which includes a knife and means for actuating it, a carriage and means for guiding the carriage past the cutting edge of the knife, a normally fixed slice support positioned adjacent said carriage and lying substantially in the supporting plane of said carriage, adapted to support the slice at the point of severance, and deflector means unitary with said support inclined rearwardly from the cutting plane, adapted to deflect the slices received by said support, said deflector extending below the level of the supporting plane of the carriage.

9. In a slicing machine which includes a knife and means for actuating it, a carriage and means for guiding the carriage past the cutting edge of the knife, a normally fixed slice support positioned adjacent said carriage and lying substantially in the supporting plane of said carriage, adapted to support the

slice at the point of severance, and deflector means unitary with said support, adapted to deflect the slices received by said support, said deflector means including a deflecting surface downwardly and outwardly extending from the level of the support adjacent its closest approach to the cutting edge of the knife.

10. In a slicing machine which includes a knife and means for actuating it, a carriage and means for guiding the carriage past the cutting edge of the knife, a normally fixed slice support positioned adjacent said carriage and lying substantially in the supporting plane of said carriage, adapted to support the slice at the point of severance, said support including a deflector portion unitary therewith inclined rearwardly from the cutting plane and extending below the level of the supporting plane of the carriage, adapted to deflect rearwardly away from the knife the slices received by the support, said deflector portion extending within the periphery of the knife.

11. In a slicing machine which includes a knife and means for actuating it, a carriage and means for guiding the carriage past the cutting edge of the knife, a normally fixed slice support positioned adjacent said carriage and lying substantially in the supporting plane of said carriage, adapted to support the slice at the point of severance, and deflector means including a portion unitary with said support inclined rearwardly from the cutting plane and extending below the level of the supporting plane of the carriage, and a portion mounted independently of said slice support, said portions being adapted in cooperation, to deflect the slices received by said support.

12. In a slicing machine which includes a knife and means for actuating it, a carriage and means for guiding the carriage past the cutting edge of the knife, a normally fixed slice support positioned adjacent said carriage and lying substantially in the supporting plane of said carriage, adapted to support the slice at the point of severance, and deflector means including a portion unitary with said support inclined rearwardly from the cutting plane and extending below the level of the supporting plane of the carriage, and a portion mounted independently of said slice support, said portions being adapted in cooperation, to deflect the slices received by said support, and a guard for the rear face of said knife, said additional deflector portion being mounted on said guard.

Signed at Indianapolis, county of Marion and State of Indiana, this 29th day of August, 1930.

WILLIAM J. CAMPBELL.
